(57) **CLAIM**

The ornamental design for a console for automobile or replica thereof, as shown and described.

DESCRIPTION

FIG. 1 is a front, left perspective view of a console for automobile or replica thereof, showing our new design; FIG. 2 is a front, right perspective view thereof;

FIG. 3 is a left side elevation view thereof;

FIG. 4 is a right side elevation view thereof;

FIG. 5 is a front elevation view thereof; and,

FIG. 6 is a top plan view thereof.

The dashed lines illustrate portions of the console for automobile or replica thereof forming no part of the claimed design.

1 Claim, 6 Drawing Sheets
